NORMAN L. SNOW, OF NEW CANAAN, CONNECTICUT, ASSIGNOR TO DIAMOND POWER
SPECIALTY CORPORATION, OF DETROIT, MICHIGAN, A CORPORATION OF MICHIGAN

BOILER CLEANER

Original application filed May 19, 1924, Serial No. 714,513, Patent No. 1,756,394. Divided and this application filed March 31, 1930. Serial No. 440,510.

This invention relates to boiler cleaners and has particular reference to a boiler cleaner of the character in which a blower element is adapted to direct jets of cleaning fluid 5 adjacent portions of the boiler to be cleaned.

One of the primary objects of this invention is to provide a novel means for controlling the flow of cleaning fluid to the blower element and to provide for a positive actuation 10 of this means.

This application is a division of my copending application, Serial No. 714,513, filed May 19, 1924.

Other objects and advantages of this invention, together with the numerous novel details of construction, will become more apparent as the following description proceeds, particularly when reference is had to the accompanying drawing wherein:

Figure 1 is a side elevational view of a boiler cleaner constructed in accordance with the teachings of this invention;

Figure 2 is a sectional elevational view of the structure shown in Figure 1; and

Figure 3 is an edge view of a portion of the structure shown in Figure 1.

Referring then particularly to the drawing wherein like reference characters designate corresponding parts throughout all views, there is disclosed in Figure 1 a blower element 10 which is rotatable in a head designated generally by the reference character 11, the blower element being provided with nozzles (not shown) for discharging jets of cleaning fluid adjacent portions of the boiler to be cleaned.

The blower head includes a gooseneck 12 in which one end of the blower element is rotatably mounted, the other end of this gooseneck being provided with the valve casing 13 in which a valve 14 is mounted for controlling the flow of cleaning fluid through the gooseneck to the blower element. The blower element is adapted to be rotated by suitable means which may, as illustrated, include the chain wheel 15, the pinion 16 and the gear 17 which meshes with the pinion.

The valve is actuated upon rotation of the blower element by suitable means which includes the lever 18 and the cam 19 fixed to

one side of the gear 17 for rotation with the same.

Referring then particularly to Figure 2 of the drawing, it will be noted that the cam 19 is preferably concentric with the blower element 10 and is provided with the spaced ends 29 and 30. The actuating lever 18 is pivotally mounted intermediate its ends as at 32 upon the lug 33 extending upwardly from the valve casing 13.

One of the oppositely extending end portions 35 of the lever has an offset lug 36 provided with faces engageable with the cam for swinging the lever to open the valve. 65 This end portion has the inclined end face 37 which, when the lever is in its normal inoperative position, is engageable with the inner edge of the end 29 of the cam and over which this edge rides upon clockwise rotation of the blower element and cam. After the inner edge of the cam end has passed beyond the end of the lug 36, the inner face of the cam rides over the curved face 38 upon the end portion 35 holding the lever in adjusted 70 position and thereby holding the valve open. When the end 30 of the cam passes over the curved face 38, the transverse face 39 of the end portion 35 rides over this end of the cam, allowing the lever to gradually return toward its original position until the end 30 passes beyond this transverse face, after which the lever is allowed to return immediately 75 to its original position.

For the purpose of positively returning the valve actuating lever and also closing the valve, the other oppositely extending end portion of the lever is provided with the offset lug 41 having the lower face 42 which is engageable with a suitable projection such as the pin 43 upon the gear wheel to thereby raise this end portion of the lever and return the same to its original position if it has not previously reached this position. 85 Also, this end portion 40 of the lever is connected to the valve stem 44 by the link 45 to insure the positive closing of the valve. The arrangement of parts is such that when the pin 43 is passing the end portion 35 of the lever, the latter is in its inwardly adjusted 95 100

position so that the pin does not contact with the same.

From the above it will be apparent that the invention provides means for effecting an actuation of the cleaning fluid control valve upon rotation of the blower element. It will be noted that this means includes a lever which is connected to the valve stem together with a positive means for effecting an actuation of this lever in both directions about its pivot. Thus the valve will be positively actuated to open and closed position during rotation of the blower element.

For the purpose of conveniently describing the invention, reference has been made throughout the specification to the construction as a boiler cleaner adapted to clean parts of a boiler. It will be apparent, however, that the invention may be incorporated in a cleaner for any type of a heat exchange apparatus, and it is to be therefore understood that the term "boiler" wherever used in the specification or claims is to be construed as meaning a heat transfer apparatus or fluid heater of any character, and the term "boiler cleaner" is to be construed as meaning a cleaner for any such apparatus.

While the invention has been described with considerable detail, it is to be understood that the description is for the purpose of illustration only and is not definitive of the limits of the inventive idea. The right is therefore reserved to make such changes in the details of construction and arrangement of parts as will fall within the purview of the attached claims.

What I claim as my invention is:

1. In a boiler cleaner, the combination with a blower element, of a valve for controlling the admission of cleaning fluid thereto, a pivotal lever so associated with the valve that swinging movement of the lever effects an actuation of the valve, and means operable upon continuous movement of said blower element in one direction for positively swinging the lever in opposite directions.

2. In a boiler cleaner, the combination with a rotatable blower element, of a valve for controlling the admission of cleaning fluid thereto, a lever pivoted intermediate its ends and so arranged with respect to the valve as to actuate the same, means rotatable with said blower element and engageable with an end portion of said lever for swinging the same in one direction, and means also rotatable with said blower element and engageable with the other end portion of said lever for swinging the same in an opposite direction.

3. In a boiler cleaner, the combination of a movable blower element, a valve for controlling the flow of cleaning fluid to the blower element, a pivotal lever so associated with the valve as to actuate the same, a cam movable with the blower element and engageable

with said lever for moving the lever in one direction about its pivot, and a pin movable with said blower element and engageable with said lever for moving the lever in the other direction about its pivot.

4. In a boiler cleaner, the combination of a rotatable blower element, a valve for controlling the flow of cleaning fluid to the blower element, a pivotal lever so associated with the valve as to actuate the same, and members rotatable with the blower element and successively engageable with the pivotal lever upon continuous rotation of the blower element in one direction for moving the same in opposite directions about its pivot.

5. In a boiler cleaner, the combination of a movable blower element, a valve controlling the flow of cleaning fluid to the blower element, a lever connected with the valve, and members movable with the blower element and arranged to successively engage the lever upon continuous movement of the blower element in one direction to move the valve to open and closed positions.

6. In a boiler cleaner, the combination of a rotatable blower element, a valve for controlling the flow of cleaning fluid to the blower element, a lever connected to the valve for actuating the same, a cam rotatable with the blower element and engaging the lever to move the valve in one direction, and a pin rotatable with the blower element and engageable with the lever for moving the valve in the other direction.

7. In a boiler cleaner, the combination of a blower head, a rotatable blower element, a valve fixed against rotation with said blower element for controlling the flow of cleaning fluid to the blower element, and means for actuating said valve including a cam rotatable with the blower element and a lever pivoted intermediate its ends on said head and connected to the said valve, said lever having an end portion engageable with the inner periphery of said cam for actuation by the same.

8. In a boiler cleaner, the combination of a rotatable blower element, a valve for controlling the flow of cleaning fluid to the blower element, and means for actuating said valve, said means including a cam rotatable with the blower element, a lever pivoted intermediate its ends and connected to the valve, said lever having an end portion engageable with the inner periphery of said cam for actuation by the same, and a pin rotatable with said blower element and engaging said lever for moving the same in a direction opposite to the movement imparted to the lever by the cam.

9. In a boiler cleaner, the combination of a rotatable blower element, a cam rotatable with the blower element, a pin rotatable with the blower element, a valve for controlling the flow of cleaning fluid to the blower ele-

ment, and a lever pivoted intermediate its ends and connected to said valve for actuating the same, said lever having an offset end portion engageable with the inner periphery of the cam for actuation by the same to effect an opening of the valve, said offset end portion having an inclined face providing for a relatively slow initial closing of the valve, and said lever also having a second offset end portion engageable with said pin for effecting an actuation of said lever to effect a positive closing of the valve.

10. In a boiler cleaner, a rotatable blower element, a head in which said blower is journaled, a valve for controlling the flow of cleaning fluid to said blower element, and means for actuating said valve upon rotation of said blower element, said means including a lever pivoted intermediate its ends to said head, a cam fixed for rotation with said blower element and engageable with said lever for moving the same in one direction about its pivot, and a pin rotatable with said blower element and engageable with the other end of said lever for moving said lever in the other direction about its pivot.

11. In a boiler cleaner, the combination of a rotatable blower element, a valve controlling the flow of cleaning fluid to the blower element, a lever connected to said valve for actuating the same, and members rotatable with said blower element and arranged to successively engage said lever upon continuous rotation of said blower element in the same direction to move the valve to open and closed positions.

In testimony whereof I affix my signature.
NORMAN L. SNOW.
